UNITED STATES PATENT OFFICE.

MORRIS ECKSTEIN, OF CHICAGO, ILLINOIS, ASSIGNOR TO HERMAN KAUFMAN AND
FRANK KESSLER, BOTH OF CHICAGO, ILLINOIS.

DISPENSING DEVICE.

1,291,804.

Specification of Letters Patent. Patented Jan. 21, 1919.

Application filed April 25, 1918. Serial No. 230,639.

To all whom it may concern:

Be it known that I, MORRIS ECKSTEIN, a citizen of the United States, and a resident of Chicago, in the county of Cook and State of Illinois, have invented certain new and useful Improvements in Dispensing Devices, of which the following is a specification.

This invention relates to improvements in a device or apparatus to be used for dispensing measured or predetermined quantities of granulated, powdered or finely pulverized material from a closed receptacle or container, and while the invention is particularly intended for use in cafeterias or self-help restaurants or dining places for dispensing or discharging sugar therefrom into tea and coffee cups, or on articles of food, yet it is applicable for use in other places, and may be employed for dispensing other kinds of material, and for this reason, I wish it distinctly understood that I do not wish to be limited in its application or in the kind of material to be dispensed.

The principal object of the invention is to provide a device or apparatus of the above mentioned general character, which shall be simple and inexpensive in construction, attractive in appearance, strong, durable and efficient in operation, which can be suitably supported on a table or stand at a desired height therefrom to permit of vessels being placed under the dispenser to receive sugar or material from the same. Another important object is to so construct the device that a highly sanitary dispenser will be provided, that is to say, one in which the material cannot be contaminated or deleteriously affected by placing wet or used spoons therein, as often occurs in sugar bowls of the ordinary kind used in public dining places. A further object is to provide a dispenser of such construction as to prevent waste of sugar or material and which can be operated from opposite points, if desired.

Various other objects and advantages will be disclosed in the subjoined description and explanation.

The invention consists in certain peculiarities of the construction, novel arrangement and operation of the various parts thereof, as will be hereinafter more fully set forth and specifically claimed.

In the accompanying drawings which serve to illustrate an embodiment of the invention—

Figure 1 is a view in side elevation of a

dispensing device embodying the invention showing it mounted on an upright supporting frame.

Fig. 2 is a central vertical sectional view 60 of a portion of the container for the material to be dispensed or discharged and its discharging funnel or hopper, the said view being taken on line 2—2 of Fig. 3 looking in the direction indicated by the arrows. 65

Fig. 3 is a plan view partly in section and partly in elevation taken on line 3—3 of Fig. 2 looking in the direction indicated by the arrows.

Fig. 4 is a bottom plan view taken on line 70 4—4 of Fig. 2 looking in the direction indicated by the arrows.

Fig. 5 is a detached perspective view of the measuring and dispensing members of the device showing them in position for their 75 assemblage together, and

Fig. 6 is a sectional view taken on line 6—6 of Fig. 3 looking in the direction of the arrows showing the means of mounting the stop and guide for the projections of the rotary dispensing members. 80

Corresponding numerals of reference refer to like parts throughout the different views of the drawings.

The reference numeral 10 designates the 85 upwardly extended legs of a supporting frame 11, the lower ends of which legs are adapted to rest on a table or stand, and if desired, may be secured thereto in any suitable way. Mounted on the upper portion 90 of the legs 10 or frame 11 so as to extend downwardly between said legs is a funnel shaped discharging hopper 12 which terminates at its lower end in an annular spout 13 of any suitable size. Located vertically 95 above the upper end of the hopper 12 is a container or receptacle 14 for the sugar or other material to be dispensed, which container may be made of any suitable size, form and material, but by preference, cylindrical in shape and of metal. The upper end of the container 14 may be closed by means of a suitable cap or cover 15 detachably mounted thereon so as to permit material to be supplied to the container. Horizontally 100 located in the lower end of the container 14 and fixed thereto by means of screws 16, or otherwise, is a measuring or pocketed member 17 which is provided with a number of openings 18 each being of a size to hold the 110 desired amount or quantity of material when the upper and lower ends of each of said

openings are closed, to be dispensed. As shown in the drawings, these openings are located in a circle around the vertical axis of the member 17 and near the periphery of said member and may be of any desired number. As shown in Fig. 2 of the drawings the openings 18 extend entirely through the member 17 and are adapted to communicate at their upper ends with the container 14 and at their lower ends with the funnel or hopper 12 under certain conditions in the operation of the parts of the device. The lower portion of the container 14 and the upper part or end of the funnel or hopper 12 are united on their outer surfaces by one or more internally channeled members 19, which members act as guide-ways for the projections or handles on one of the rotary members of the dispenser, as well as for stops to check the rotary movement of said member. In Figs. 3 and 4 of the drawings, the receptacle 14 is shown as being equipped with two of the members 19 which are located diametrically opposite each other. Each of these members has on one of its ends an outwardly extended projection 20 against which the finger of the operator will contact in the operation of the device, as will be presently explained. As shown in Figs. 1, 3, 4 and 6 of the drawings the upper horizontal wall of each of the members 19 is connected to the outer surface of the container 14 at a suitable distance from the lower end of said container, and the lower wall of each of said members is connected to the hopper 12 at its upper portion. By this arrangement it is evident that a slight horizontally disposed space will be provided between the lower end of the container and the upper end of the hopper or funnel 12 in which is located a horizontally rotatable controlling member or disk 21 which is provided near its periphery with a single opening 22 which is by preference slightly larger than the openings 18 in the pocketed member 17, with which openings the opening 22 is adapted to register successively. The disk or controlling member 21 is provided at its periphery with an upwardly extended annular flange 23 which surrounds the lower portion of the container 14 and is provided on its outer surface with a plurality of spaced apart projections 24, usually about six in number. These projections or handles are adapted to pass through the channeled member or members 19 in the operation of the device and are so located on the flange 23 of the controlling member 21, that by placing the thumb on the outer surface of one of the projections 20 of the members 19, the fore-finger of the hand when extended will reach to and engage the projection 24 adjacent to said projection; when by pressing said finger toward the thumb against the handle or projection 24 the disk or mem-

ber 21 will be caused to turn sufficiently to move the opening 22 out of register with the opening 18 from which the material has been discharged and into register with another one of said openings containing sugar or material. As soon as this has been done it is apparent that the material in the pocket or opening 18 with which the opening 22 has just been brought into register will be discharged into the hopper or funnel 12 and from thence through the spout 13 thereof into the cup or receptacle which may be placed under the container. Mounted on top of the pocketed member 17 is a shut-off plate 25 which is substantially semi-circular or segmental in shape and has an angular opening 26 in which a correspondingly shaped head 27 on a slotted screw bolt 28 fits when the parts are in their assembled positions. The screw bolt 28 is extended through a suitable opening in the center of the pocketed member 17 and through a suitable opening in the controlling member or disk 21, which latter opening is provided with a diametrically disposed rib 29 to fit in the slot 30 of said bolt. The plate 25 is of such size as to cover at least three of the openings in the pocketed member as shown. On the lower part of the bolt 28 is screwed a tube 30 which projects downwardly through the nozzle or spout 13 of the funnel or hopper 12 and provides means for regulating the tension of a spring 31 which is coiled around the bolt 28 and rests at one of its ends against the lower surface of the controlling disk or member 21 and at its lower end against the upper end of said tube. It is quite important that the shut-off plate or member 25 and the controlling disk or member 21 should fit closely against the upper and lower surfaces, respectively, of the pocketed member 17 yet so as to be turned on said member and by the foregoing arrangement of the bolt 28, tube 30 and spring 31 associated with said members as above set forth it is apparent that the tension of the spring 31 can be regulated by turning the tube 30 in the proper direction on the bolt 28 so as to create the desired pressure of the plates 25 and 21 against the pocketed member in order to prevent accumulation of sugar or material between said plates or members and the pocketed member. As the tube 30 is extended centrally through the nozzle 13 of the hopper or funnel 12 it is manifest that the sugar or material will be discharged from the funnel in the form of a ring or circle.

While I have shown the device provided with two of the channeled members 19 separated from each other, thus providing spaces between said members for the exposure of the handles 24 at opposite sides of the container, yet it will be understood that one of said members 19 only may be employed and that when such is the case it can be extended

as far around the container as may be desired so as to provide only one space for the exposure of the handles on the rotary or controlling member. From the foregoing and by reference to the drawings it will be clearly understood and readily seen, that by supplying the container 14 with a quantity of sugar or other material, and assuming that the parts are in the positions shown in Figs. 5 2 and 3 of the drawings and all of the pockets or openings 18 have been filled, it is evident that by placing the thumb on the outer surface of one of the projections 20 and the forefinger over one of the projections 24, 10 the controlling member or disk 21 may be turned so that the opening 22 therein will register with one of the pockets 18 from which the sugar or material will be discharged into the hopper or funnel 12 and 15 20 from thence through the spout 13 into the cup or vessel. As the shut-off plate 25 is fixed to the head 27 of the bolt 28, and as the disk 21 is also fixed to said bolt it is obvious that they will be turned in unison and that 25 the opening 22 in the controlling disk 21 will be caused to register successively with the openings or pockets 18 of the pocketed member.

Having thus fully described my invention, 30 what I claim as new and desire to secure by Letters Patent is—

1. In a dispensing device, the combination with a suitably supported container, of a member fixed to the lower portion thereof 35 and having a plurality of openings extended vertically therethrough, a discharging funnel located below said member, a plate rotatably located on the upper surface of the said member and adapted to close the openings therein, a controlling disk having an opening therein and mounted for rotation below said member, means uniting the disk and plate to cause them to move in unison when the latter is turned, a plurality of 40 45 handles extended from the disk, and a channeled member mounted horizontally at the periphery of the disk for the passage therethrough of said projections and to act as a stop for the finger of the operator.

2. In a dispensing device, the combination with a suitable supported container, of a member fixed to the lower portion thereof and closing the same, a discharging funnel located below said member, said member 55 having a plurality of openings extended vertically therethrough and communicating with the container and funnel, a plate located on the upper surface of the said member and adapted to close a plurality of the 60 openings therein, a controlling disk having an opening therein and mounted below said

member, means uniting the disk and plate for rotary movement in unison on the said member, a plurality of handles extended radially from the disk in spaced relation to one another, and a channeled member mounted horizontally at the periphery of the disk for the passage therethrough of said projections and to act as a stop for the finger of the operator. 65 70

3. In a dispensing device, the combination with a suitably supported container, of a discharging funnel located below the same, a member fixed to the lower portion of the container and closing the same, said member having a plurality of openings communicating with the container and funnel, a plate located on the upper surface of the said member and adapted to close at least three of the openings therein, a controlling 80 disk having an opening therein and mounted below said member, means uniting the disk and plate for rotary movement in unison on said member, a plurality of handles extended radially from the disk and in 85 spaced relation to one another, and a pair of channeled members mounted horizontally at opposite points at the periphery of the disk for the passage therethrough of said projections and to act as stops for the fingers 90 of the operators.

4. In a dispensing device, the combination with a suitably supported container, of a discharging funnel located below the same, a member fixed to the lower portion of the 95 container and closing the same, said member having a plurality of openings communicating with the container and the funnel, a plate located on the upper surface of the said member and adapted to close at least 100 three of the openings therein, a controlling disk having an opening therein and mounted below said member, a screw bolt rotatably mounted in the said member and uniting said plate and disk together to move in unison, a spring surrounding said bolt below the disk and in contact therewith at one of its ends, a tube screwed onto the lower portion of said bolt in contact with the lower end of said spring and extended through 105 the discharged orifice of the funnel, a plurality of handles extended radially from said disk and in spaced relation to one another, and a channeled member mounted horizontally at the periphery of the disk for 110 passage therethrough of said handles or projections and to act as a stop for the finger of the operator. 115
